SIMON ROTH, OF BROOKLYN, NEW YORK, ASSIGNOR OF SIXTY-SIX AND TWO-THIRDS
PER CENT TO ELIZABETH FISHER, OF BROOKLYN, NEW YORK.

HEEL FOR FOOTWEAR.

Application filed July 19, 1927. Serial No. 206,836.

This invention relates to heels for footwear, especially women's shoes, pumps, slippers or the like, which are provided with wooden heels having thereon a final lift of 5 leather or rubber, which constitutes the walking surface.

The object of the invention is to make the final lift, which constitutes the walking surface, removable from the heel so that it may 10 be readily removed from the heel and replaced by a new lift.

Further objects of the invention are to secure the final lift to the heel without the use of nails, which have a tendency to split the 15 heel, and to strengthen the wooden heel by providing a metal reinforcement therein.

In the drawings, Fig. 1 represents a vertical section of a wooden heel; Fig. 2 is a vertical section on line 2—2 of Fig. 1; Fig. 20 3 is a horizontal section on line 3—3 of Fig. 1; Fig. 4 is a side view of the final lift which constitutes the walking surface and the attaching post secured thereto; Fig. 5 is a view of the under side of the heel with the device of 25 Fig. 4 removed therefrom; Fig. 6 is a top view of the device shown in Fig. 4; Fig. 7 is a view similar to Fig. 1 embodying a locking device for the final lift; Fig. 8 is a vertical section on the line 8—8 of Fig. 7.

30 The heel 1 is preferably made of wood or other composition and is provided with the usual concave surface 2 whereby it is secured to the body of the shoe. The chamber 3 is formed substantially centrally in the under 35 side of the heel, and is provided with a metal lining 4 extending substantially to the top of the chamber 3. The lining 4 is provided with a flange or ears 5 bent at right angles to the sides of the lining and secured to the 40 heel by the brads 6. The under surface of the heel is slightly recessed so that the flange or ears 5 and the nail heads should not extend beyond the lowermost surface of the heel. A securing member 7 is positioned across the 45 lining 4 with its ends attached to the lining and may consist of a flat piece of metal in which form it is shown in the drawings, or may be wedge shaped as desired. The securing member 7 is located centrally in the 50 chamber 3. The lift 8, which constitutes the walking surface of the heel, is preferably made of leather although it may be made of rubber or other composition and has secured thereto the post 9 by means of the flange 10

post and the brads 11 passing into the body of the lift 8. The post 9 is provided with two slots 12 and 12^a which are formed opposite one another and extend more than half way down the sides of the post. In order to secure the lift to the heel, the post 9 is inserted 60 into the chamber 3 so that the slots 12 and 12^a are aligned with the securing member 7 and by pressure on the lift 8 the side walls of the slots are caused to embrace the securing 65 member 7. Inasmuch as the fit of the post 9 against the lining 4 is snug and the thickness of the securing member 7 is slightly greater than the width of the slots 12 and 12^a, the securing member will spread or force the arc-shaped upper portions 13 and 13^a outwardly 70 to cause them to frictionally engage with the lining 4 and retain the lift 8 in position.

The lift 8, when it is worn, may be removed and a new lift carrying a post 9 substituted. 75 It will be noted that by reason of the projection of the securing member 7 into the slots 12 and 12^a, it is not possible for the lift 8 to turn or change its position with respect to the heel proper, thus ensuring that the contour of the periphery of the heel from top to bottom will always be uniform. Another of 80 the important advantages arising out of the use of this feature resides in the fact that it is necessary to utilize but one post inasmuch 85 as the inability of the lift to turn is obtained by the type of securing means and non-turning means employed.

In Figs. 7 and 8, a locking member is illustrated and consists of the leg 14 secured to the 90 inside wall of the lining 4 bent at its free end to form the lock 15 fitting into the recesses 16 and 17 formed respectively through the wall of the post 9 and through the lining 4. A groove 18 is formed in the lowermost edge of 95 the heel 1 so that when it is desired to detach the lift this can be done by inserting a pin or nail into the groove 18 against the lock 15 and forcing it backwardly out of the recesses 16 and 17, and while it is retained in this 100 position pulling the lift away from the heel.

I claim:

1. A heel for footwear, comprising a heel body, a recess in the heel, a metal lining for the recess, a lift, a post on the lift, a slot on 105 the post, securing means across the recess, said securing means entering the slot and spreading the sides of the post against the lining to retain the same in frictional contact and securing the lift from turning. 110

2. A heel for footwear comprising a heel body, a circular recess therein, a metal lining in the recess, a lift, a hollow post on the lift, said post being of a size to snugly fit the said recess, slots in the post, and a securing member positioned across the recess, the said slots being adapted to receive said securing member, and the securing member being of sufficient thickness to spread the upper portion of the post outwardly against the lining in the recess and thereby secure the lift and post from displacement.
- 5 3. A heel for footwear comprising a heel body, a circular recess therein, a metal lining in the recess, a lift, a hollow post on the lift, said post being of a size to snugly fit the said
- 10
- 15

recess, slots in the post, a securing member positioned across the recess, the said slots being adapted to receive said securing member, and the securing member being of sufficient thickness to spread the upper portion of the post outwardly against the lining in the recess and thereby secure the lift and post from displacement, and a locking member comprising apertures in said post and in said lining, a lock fitting therewith and a groove in the heel through which the lock may be released. 20 25

In witness whereof I have hereunto set my hand.

SIMON ROTH.
